UNITED STATES PATENT OFFICE.

FRANCIS J. DOWLING, OF NEW YORK, N. Y.

DOORLOCK.

Application filed August 24, 1925. Serial No. 51,919.

This invention relates to locking devices and has particular reference to locks of jimmy-proof character.

Among the objects of this invention is to provide a lock having a strike which is attached to the jamb in a novel manner, being reenforced to prevent the same from being so separated from the jamb, by wedge shaped tools or the like that are commonly employed to pry off the strike of a jimmy-proof lock or similar device, as to limit the inward swing of the door should the strike be pried loose.

Another object of this invention is to provide a lock having a movable member which is preferably in the form of a chain or the like and adapted for use in connection with the lock casing to limit the degree to which the door may be opened, but said chain being likewise adapted as an anchorage for the strike to limit the opening of the door when the strike is pried from the jamb.

Another object of this invention is to provide a lock having a movable member such as a chain, and a compound bolt which is adapted for closing the lock and preferably in a jimmy-proof manner, said bolt being also adapted to engage said movable member, said movable member being connected to the jamb whereby a forcible entry as by prying the strike from the jamb is rendered impossible, said movable member being also engageable with said casing in such manner as to permit the door to be slightly opened.

Another object of this invention is to provide a lock having a movable member such as a chain which is connected to the jamb and is engageable either with the bolt of the lock or directly with the lock casing depending upon whether it is desired to retain the door in closed or slightly open position.

Another object of this invention is to provide slots in the casing so as to allow for the adjustment of the lock to correspond with the strike irrespective of the tendency of the parts to become out of alinement, due to sagging, warping, shrinking, or the like.

It being understood that the usual manner in which a burglar attacks a jimmy-proof lock is by inserting a chisel or the like between the door and jamb and forcing the chisel beneath the flange of the strike with

the result that the screws holding this flange to the jamb are loosened; it becomes then a relatively easy matter to open the door by exerting sufficient pressure inward thereon to detach the remaining screws which secure the strike to the face of the jamb. This invention seeks to prevent that condition by means set forth more particularly hereinbefore. The invention includes generally a holding means which can be secured to the jamb remotely from the edge thereof and in spaced vertical relation to the lock casing whereby a plurality of holding members can be used, said holding members being adapted for use both when the door is closed and when it is open, being available in all cases to hold the door slightly ajar.

Still another object of this invention is to provide a novel anchor plate for holding the barrel of the lock in place and whereby a material saving in time and labor is effected when the lock is being mounted upon the door.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a horizontal section of a portion of the lock, the lock being shown mounted and in locked position.

Fig. 2 is a similar view in elevation.

Fig. 3 is an edge view of the strike.

Fig. 4 is a view in elevation showing the lock mounted in operative position, parts of the lock being in section to show a step in opening the lock.

Fig. 5 is a view in elevation showing a typical use of the lock with the door slightly ajar.

Referring now more specifically to the drawings, I show my lock as comprising a casing 10 mounted upon a door 11, and a strike 12 upon a jamb 13. Movable means is mounted upon the jamb so arranged as to be adapted to strengthen the locked condition as between the door and the jamb, said movable means being for this purpose conceived of as a device which is engageable with the strike to reenforce the same in its

22

attachment to the jamb, or as a device which is engageable directly with means borne by the door such as the bolt of the lock, but preferably in such manner as to engage 5 said bolt through the strike whereby the strike is reenforced and direct engagement with the bolt secured. Said movable means is shown in the form of a flexible device such as the chains 14 which are secured to 10 the jamb in any suitable manner or position but preferably by anchor members 15 spaced somewhat from the edge of the jamb and in spaced vertical relation to the strike as for instance above and below the same. 15 The chains, any desirable number of which may be used, have connection with a central keeper or link 16 which is suitable for the purpose. The vertical pull upon the chains is balanced and a reenforcement of uniform 20 character produced.

The master link or keeper 16 is engageable with means at the strike or upon the lock casing. Thus the strike is provided with an opening 17 through which the link 25 is insertable into the strike in position to be engaged by a bolt having a compound motion or otherwise suitably arranged for the purpose. More specifically said bolt comprises an outer rigid member or shell 18 30 within which a locking member 19 is movable, for engagement with the link by means of a tongue 20. Preferably a plurality of said locking members are provided to engage said link simultaneously from both sides 35 thereof. Suitable means are provided for causing said locking members to engage the link when the bolt is projected and to release the same when the bolt is partially retracted in relation to the casing. Thus 40 I provide automatic means such as the springs 21 which are operative to cause the locking members to move out of engagement with the master link. The locking members 19 are arranged for oscillation as by 45 being mounted upon pins 22 secured in the shell 18 and which support also the springs. The locking members are for this purpose grooved at 23 as shown in Fig. 1 thus providing a pair of lugs 24 on each member 50 between which a spring is positioned. The springs bear between the inner end of the shell 18 of the bolt and the shoulder portions of the locking members at said grooves so as to throw said members to the sides of the 55 shell or away from each other. As means for actuating the locking members toward the central axis of the lock for engagement with the master link, the lugs 24 are made of extended size to engage a portion 25 of the 60 end wall of the lock casing adjacent to the striking edge of the door, to cause a tilting of said locking members when said lugs strike the same as the bolt is projected. The member 25 is thus seen as dividing the opening 65 in the lock casing into a plurality of smaller openings similar to those seen in the strike in Fig. 3. The shell 18 is thus seen to be of approximately U-form. The sides of the U are preferably flanged at the ends, at the sides, and also at the crotch of the U as shown at 26, 27, and 28, respectively, thus forming a sort of box construction, within which the locking members 19 are positioned at the sides of the U, the pins 22 engaging opposite flanges 27 on each side 70 of the shell. When the bolt is slightly retracted into the casing as shown in Fig. 4 the lugs 24 move out of abutment relation with the member 25 and the springs 21 tilt the locking members to the sides of the shell 75 till they strike the sides of the U. The strike is provided with means for properly supporting the master link in position to be engaged by the locking members. Thus I provide an opening 29 opposite to the opening 17, the link being supported in both of said openings. Due to the form of the shell 18 the master link is readily insertable into the openings 17 and 29 whether the bolt is projected partially into the strike or retracted 80 therefrom, and thence the operator desiring to leave the building and yet cause the lock to assume the condition as in Fig. 2, may insert the keeper into the strike before he passes out, and when the bolt is projected 85 into the strike it will interlock with the keeper as shown. Should the strike be forcibly detached from the jamb by burglars, the chains as in Fig. 1 would hold the strike and prevent the door from being opened. 10

As long as the bolt remains in projected position the master link can not be disengaged from the bolt. To prevent the detachment of the strike from the lock casing means, as for instance by withdrawing the bolt from the strike and dragging the link along with it, abutment means is provided in the strike to limit relative movement of the parts movable in the strike. Said abutment means takes the form preferably of a 110 member 30 extending across the front wall of the strike and dividing the opening therein into a pair of openings. The member 30 lies in the path of the master link and prevents withdrawal of the bolt and keeper 115 interlocked therewith from the strike toward the casing except in the normal manner by unlocking the locking members 19. The lock is jimmied-proof also in the broad aspect 120 of a bolt having locking members 19 the tongues 20 of which are movable to engage or interlock behind or abut against the member 30 though I prefer to arrange my invention as set forth hereinbefore with the link interlock. When the door is jimmied 125 the bolt maintains its projected relation to the casing, and hence the lugs 24 and abutment 25 keep the locking members projected behind the abutment in position to impinge against it, thus limiting the degree 130

of separation between the door and the jamb to the available clearance normally between the tongues 20 and the abutment 30.

Engaging or hook means 31 is mounted upon the lock casing as by means of a shank 32 screwed into the casing, said hook extending preferably transversely of the lock. The master link may be engaged with said hook by being slipped lengthwise thereover and then turned through a quarter turn as shown in Fig. 5 to provide a reliable engagement. The length of the link is thus available to permit the door to be opened to a predetermined degree that will depend upon the length of the chains and the size of the master link.

The normal method of using the lock whether closing up for the night or to leave the premises is to place the master link in position in the strike, and then to close the lock by means of a knob 33. If the operator is within the house, and, answering a call of a person desiring admittance, wishes first to see the newcomer, he will avail himself of the chains to secure the door so that the same can be opened only slightly. To do this, the bolt is first retracted slightly as shown in Fig. 4 to release the master link. In the meantime the door is still held locked by the bolt shell 18, and the operator then engages the link with the hook 31, after which the bolt is wholly retracted and the door opened to such degree as the chains permit.

Barrel mechanism 34 is indicated projecting through a hole in the door 11 and including a feather pin 42 which projects through a plate 37 having a center structure 40 with a large hole 41 through which the feather pin projects loosely so as to prevent binding or cramping of the key or barrel mechanism as a result of vertical adjustments of the casing 10 with respect to the door.

To provide for vertical movement of the lock casing along the door as for purposes of adjustment of the lock when the door sags, I provide a plurality of slots 52 through which the wood screws 53 are engaged with the door. The slots extend uniformly in the same or vertical direction and thus provide for the desired vertical play or movement of the lock casing. It is obvious that this principle can be employed on any and all parts of the lock as may be deemed essential.

65 I claim:

1. In a door lock, the combination with a door member and a jamb member, of a lock casing on the door member, a bolt projectable therefrom, a strike upon the jamb member, and movable means mounted upon the jamb and engageable with the strike for interlocking with the bolt or with the lock casing for holding the door when the bolt is retracted.

2. In a door lock, the combination with a door and a jamb, of a bolt and a lock casing

upon the door, and means including a strike upon the jamb, engageable with the bolt, the means upon the jamb comprising also a movable member engageable with the bolt while the same is engaged with the strike to reinforce the strike.

3. In a door lock, the combination with a door and a jamb, of means including a lock casing and bolt mounted upon the door and means upon the jamb including a strike and a movable member, said lock casing carrying said bolt and means to cause the bolt to engage the strike, said movable member being engageable with said bolt, the means upon the door comprising also engaging means other than the bolt, said movable member being engageable with said engaging means whereby the door may be retained in varied positions.

4. In a door lock, the combination with a casing on the door, a strike on the jamb, a movable member on the jamb arranged to enter the strike, said casing having a bolt to engage said movable member within the strike, and anchor means on the door engageable with said movable member after the same has been disengaged from the bolt to permit the door to be retained ajar.

5. In a door lock, the combination with a door member and a jamb member, of a lock casing on the door member, a bolt projectable therefrom, a strike upon the jamb member, movable means mounted upon the jamb and engageable with the strike and interlocking with the bolt, and anchor means on the door engageable with the movable member in another position thereof for retaining the door ajar.

6. In a door lock, the combination with a casing and a strike, of a bolt carried by one of said parts, and abutment means carried by the other part, the bolt having a relatively movable member therein for engaging said abutment means, said member being provided with a lug, the part having the bolt being provided with means stationary relatively to the bolt for engaging said lug to move said member when the bolt is projected and to retain the same in changed position.

7. In a door lock, the combination with a casing and a strike, of a bolt of U-form borne by the casing, and an abutment member borne by the strike receivable by the bolt through the open end of the U when the bolt is projected, said bolt having a plurality of locking members at the legs thereof which are caused to tilt when the bolt is projected to bring the locking members into position to engage said abutment means.

8. In a door lock, the combination with a casing and a strike, of a bolt of U-form borne by the casing, and an abutment member borne by the strike, said bolt having a plurality of locking members at the legs thereof which are caused to tilt when the bolt

is projected to bring the locking members into position to engage said abutment means, said casing being provided with a member arranged to enter between the sides of the U 5 as the bolt is projected to cause said locking members to tilt as aforesaid.

9. In a door lock, the combination with a casing and a strike, of a bolt of U-form borne by the casing, and an abutment member 10 borne by the strike, said bolt having a plurality of locking members at the legs thereof which are caused to tilt when the bolt is projected to bring the locking members back of said abutment means, movable means being 15 provided for re-enforcing the strike, said movable means being engageable with said locking members after they are tilted, and said casing having a hook to engage said movable means when the same is disengaged 20 from the aforesaid locking members.

10. In a door lock, the combination with a casing and a strike, of a movable member adapted to be secured to the jamb, said casing having a bolt to engage within said 25 strike, said strike being arranged to receive said movable member to cause the bolt to interlock with said member, said bolt being adapted to disengage from said movable member when the bolt is slightly retracted, 30 but while still in engagement with the strike, and means carried by the door and engageable with said movable member after the same has been detached from the bolt and before the bolt has been wholly retracted.

11. In a door lock, the combination with a member carried by the door, a bolt movable with relation thereto, and movable means adapted to be borne by the jamb and engageable with the door member, said movable 40 means being engageable with said bolt or with the door member according to the position in which the door is to be retained with respect to the jamb.

12. In a door lock, the combination of a 45 casing adapted to be borne by a door, a movable keeper member adapted to be borne by a jamb, said casing having a movable locking bolt, said movable keeper member being engageable positively with said bolt when 50 the bolt is moved along the casing, and hook means adapted to be carried by the door and engageable with said movable member after the same is disengaged from the bolt according to the position in which it is de- 55 sired to retain the door.

13. In a door lock, the combination of a 60 casing for a door, a strike for a jamb, said casing having a bolt to engage the strike, and a flexible member adapted to be secured 65 to the jamb, abutment means being provided in the strike, said flexible member being engageable with the bolt in the strike, said abutment means being operative in conjunction with the flexible member to prevent 70 withdrawal thereof from the strike along

with the bolt except when the bolt is disengaged from the flexible member.

14. In a door lock, the combination of a casing for a door, a strike for a jamb, and a flexible member insertable into the strike, 70 said casing having a bolt movable into said strike after the flexible member is inserted and including means for positively engaging the flexible member.

15. In a door lock, the combination of a 75 casing for a door, a strike for a jamb, means for effecting an interlock between the strike and the casing, and a flexible member secured to the jamb and co-operating to re-enforce the strike in its attachment to the jamb. 80

16. In a door lock, the combination of means including a casing member for a door, and means including an engaging member for a jamb, said casing member having means to engage said engaging member, 85 said casing member having slots extending in a vertical direction to receive screws to fasten said member, said member being movable vertically as determined by said 90 slots and the screws therein, means being provided on the jamb including a plurality of chains to engage said engaging member and strengthen the same in its attachment to the jamb, said chains being positioned above and below the engaging member. 95

17. In a door lock, the combination with a casing and a strike, of movable means secured to a jamb and operative to hold the strike to the jamb, and anchor means on the door, said movable means being engageable 100 likewise with said anchor means to limit the opening of the door.

18. In a door lock, the combination with a casing, and a strike, of a bolt borne by the casing, said bolt having a hook, said strike 105 having an abutment around which said hook is engageable, said casing having a relatively stationary member, and the hook being so formed as to be engaged by said stationary member and moved into engaging position 110 around the abutment when the bolt is projected into the strike.

19. In a door lock, the combination with a casing, and a strike, of a movable member adapted to be secured to the jamb, said lock 115 having holding means including a bolt to engage the strike, and co-operating to interlock with the movable member, said holding means being arranged to disengage from said movable member when the bolt is slightly retracted but while still in engagement with the strike, and means carried by the door and engageable with the movable member after the same has been disengaged from the holding means and before the bolt has 120 been wholly retracted. 125

20. In a door lock, the combination of a casing for a door, a flexible member for a jamb, said casing having engaging means including a bolt, said flexible member having 130

a free end arranged to interlock with said bolt, and means associated with said flexible member and arranged to support said free end in position to be engaged by said bolt.

21. In a door lock, a casing, a strike, a bolt movable between the casing and the strike, and means auxiliary to the bolt and co-operating with the strike and constituting a means for anchoring the strike to the jamb even though the strike be loosened therefrom by an attempted forcible entry.

22. In a door lock, the combination with a lock casing for a door, a strike for a jamb, a bolt for locking the casing to the strike, said casing being movable vertically in its attachment to the door to take up the effect of the sagging of the door, actuating means for the bolt including a barrel, the door having a bore to receive said barrel, and a rotatable feather pin being provided extending between the barrel mechanism and the actuating means in the lock casing and whereby actuation of the barrel mechanism is made effective to operate the bolt, and an anchor means for the barrel comprising a plate between the lock casing and the door and having an opening to permit of free passage of said feather pin therethrough, said opening being of sufficient size to permit of verti-

cal movement of said pin therein as the lock casing is moved vertically for the purpose aforesaid.

23. In a door lock, the combination with a casing, and a strike, of a bolt carried by the casing and engageable with the strike, and a movable keeper associated with said strike, said bolt comprising a movable locking member and a housing therefor, said movable locking member having interlocking engagement with the keeper in the strike. 40

24. In a door lock, the combination with a strike having a plurality of spaced openings to receive a multiple bolt and having an abutment between said openings, of a casing, a multiple bolt slideable along said casing for entering said strike openings, said bolt including movable means for interlocking behind said strike abutment, and means carried by the casing and aligning with said abutment to cause said interlocking action of the bolt means, the casing being provided with vertical slotted connections for insuring the proper alignment of the devices aforesaid irrespective of the precise position of the door to which the casing is attached. 55

In testimony whereof I affix my signature.

FRANCIS J. DOWLING.
